FIG. 1 is a front view of a compressor for air conditioners of vehicles, according to a design of the present invention.

FIG. 2 is a rear view of the compressor for air conditioners of vehicles of FIG. 1.

FIG. 3 is a right side view of the compressor for air conditioners of vehicles of FIG. 1.

FIG. 4 is a left side view of the compressor for air conditioners of vehicles of FIG. 1.

FIG. 5 is a top view of the compressor for air conditioners of vehicles of FIG. 1.

FIG. 6 is a bottom view of the compressor for air conditioners of vehicles of FIG. 1.

FIG. 7 is a front perspective view of the compressor for air conditioners of vehicles of FIG. 1; and,

FIG. 8 is a rear perspective view of the compressor for air conditioners of vehicles of FIG. 1.
